JAMES D. NELSON, OF CINCINNATI, OHIO.

ALARM MECHANISM FOR DISTRIBUTION SYSTEMS.

1,121,593.

Specification of Letters Patent. Patented Dec. 15, 1914.

Application filed February 9, 1911. Serial No. 607,538.

To all whom it may concern:

Be it known that I, JAMES D. NELSON, a citizen of the United States of America, and resident of Cincinnati, county of Hamilton, 5 and State of Ohio, have invented certain new and useful Improvements in Alarm Mechanisms for Distribution Systems, of which the following is a specification.

This invention relates to alarm mechanisms adapted to transmit alarm signals, for the purpose of indicating variations in the apparatus to which it is attached.

Various devices are employed in connection with pressure distribution systems of 15 automatic fire extinguishing sprinklers for indicating variations of pressure in the system, or variations of flow through the system, or that the valves of the system are in the correct position. It is, however, essential to provide means for transmitting a 20 fire alarm signal, when a flow takes place through the system, which will not transmit a false alarm due to variations of pressure or other variations in the system.

An object of my invention is to produce 25 an alarm device for indicating a flow in the distribution system of an automatic fire extinguishing sprinkler, which will not transmit signals in response to variations of pressure other than those caused by a flow through the system.

A further object is to produce an alarm mechanism, which will automatically transmit 30 an alarm signal, in response to a flow of water through the distribution main of an automatic sprinkler system, and will transmit an "all right" signal when the flow has ceased.

These and other objects, I attain by means 35 of a device embodying the features herein described, and illustrated in the drawings accompanying this application and forming a part thereof.

In the drawings, Figure 1 is a plan view 40 of a clock mechanism and controlling device, which forms a detail of my invention, and Fig. 2 is a partial sectional view of an alarm mechanism, embodying my invention, in connection with a sectional view of a 45 portion of a distributing main of an automatic sprinkler system.

The apparatus illustrated as an embodiment 50 of my invention, consists of electrical transmission apparatus, a clock mechanism for controlling the operation of the transmission apparatus, pressure responsive

means for controlling the operation of the clock mechanism, and means for rendering the pressure responsive means inoperative, with respect to the clock mechanism, except 60 for variations of pressure in the distribution system, occasioned by a flow through the system.

The pressure responsive means illustrated, 65 consists of a reservoir 4, located exterior to the main 5 of the distribution system, a diffuser 6 connected with the reservoir by means of tubing 7, and a float 8 located in the reservoir and adapted to move in response to variations in the level of the liquid 70 contained within reservoir and the communicating tubing.

The diffuser consists of a flaring nozzle provided with a hollow stem 9, which projects downwardly into a vertical leg 10 of 75 the tubing, which is located within the main 5. The diffuser points in the direction of the flow through the distributing main, and its greatest diameter is a little less than the diameter of the main, so that it is capable 80 of moving from an inoperative position to an operative position, during periods of flow, and from an operative to an inoperative position, during periods of no flow. A sliding fit is provided between the stem 85 9 and the leg 10 of the tubing 7, so that the diffuser can move to different positions, without breaking the connection between the stem 9 and the tubing 7. The main 5 is enlarged in diameter by interposing a partially spherical casing 12 at a point immediately adjacent to the diffuser 6. A thin bar or spider 13 extends across the casing 12 and forms a seat for the diffuser when it is located in the operative position. 95

The reservoir 4 and the communicating tubing 7 are preferably filled with mercury, and the reservoir is so positioned relative to the normal water pressure in the main 5, that the mercury level normally 100 stands at some point, such as 14, in the tubing 7. The float 8 is supported by the mercury in the reservoir, and moves up and down in response to fluctuations of the mercury in the tubing 7. The float is provided 105 with a stem 15, which is pivotally connected to the upper end of a lever 16 and imparts the reciprocating motion of the float to the lever.

During normal conditions, or during periods 110 of no flow in the main 5, the diffuser 6 is so located in the main, that it substan-

5 tially closes off the main, so that it is im-
possible for a flow to take place through
the main, without moving the diffuser. When one of the sprinklers of the distribution system is opened, or a flow takes place
10 through the main 5, due to any other cause, the reduction of water pressure on the downstream side of the diffuser 6, causes the water pressure on the upstream side, or be-
15 low the diffuser 6, to preponderate and to move the diffuser into the casing 12, where it is held by the flow of water through the casing against the spider 13, the flow tak-
ing place through the casing, around the
edges of the diffuser. The drop in the
20 pressure, due to the flow through the cas-
ing, causes the level of the mercury in the tubing 10 to rise, and also causes the level of the mercury in the reservoir 4 to recede. In addition to this, the casing 12 and the diffuser 6 are so designed, that the passage for the water through the cas-
ing, around the edge of the diffuser, is
25 slightly restricted, so that the pressure at that point will be reduced, due to the in-
creased velocity of flow, below the pressure existing at other points in the main. This, together with the ejector action of the wa-
ter passing the mouth of the diffuser, re-
30 duces the pressure at the mouth of the dif-
fuser, and, consequently, in the tubing above the mercury, considerably below the pres-
sure existing throughout the main, and causes a resultant depression of the level of
35 the mercury in the reservoir, and, lowers the float 8.

The float controls the operation of a clock mechanism 17, through the agency of the lever 16, by moving the lug 18 on the lever 40 into and out of engagement with stops pro-
vided on a wheel 19, which forms a part of the clock mechanism. During periods of no flow through the main 5, the float 8 occupies such a position, relative to the clock mech-
45 anism, that the lug 18 contacts with a stop 20 on the wheel 19. As soon as the stop 20 is released, by lowering the lug 18 out of contact with it, the clock mechanism turns a signal wheel 21 and actuates a make and
50 break device 22, to transmit an alarm signal. The signal wheel is provided with stops 23, which are located on its periphery, and are adapted to engage a projecting arm of the make and break device 22. A stop 24 is
55 located on the wheel 19 at such a position that it will engage the lug 18 in the lowered position, after the wheel has turned through a predetermined portion of its revolution, and after the signal wheel 21 has trans-
60 mitted a distinct alarm signal, which may be varied by varying the arrangement and position of the stops 23 on the signal wheel 21. When the flow ceases through the main 5 and normal conditions are again estab-
65 lished, the mercury level in the reservoir 4

will rise, and, consequently the float will be lifted. This will raise the lug 18 out of engagement with the stop 24 and into the path of travel of the stop 20. As soon as the stop 24 is released, the clock mechanism 70 will operate to transmit an "all right" signal, and will be stopped and held in the normal position by the engagement of the stop 20 with the lug 18. The stops 23 and the wheel 21 may be so arranged, that the 75 "all right" signal differs from the alarm signal, so that it can be easily distinguished, and the connecting gear trains between the wheels 19 and 21, are so arranged that the wheel 21 will turn, so as to send the alarm 80 signal, while the wheel 19 is turning from the position in which the stop 20 engages the lug 18, to the position in which the stop 24 engages the lug 18.

It will be apparent that a change in pres-
sure within the main 5, will cause the level of the mercury in the reservoir 4, to change its position, whether the change of pressure is due to a flow through the main, or not. For this reason, I have provided means, 90 which prevents the float 15 and the intervening lever 16 from releasing the lug 20, except when a flow takes place through the main. I provide a pivotally mounted frame 26 for the clock work mechanism, which is 95 caused to occupy different positions, corresponding to variations of pressure within the main 5, by a pressure actuated dia-
phragm 27, which is exposed on one side to the water pressure within the main, and 100 which supports an arm 28 of the frame 26. The diaphragm 27, illustrated, is shown as forming a part of the wall of a chamber 29, which communicates through a passage 30, with the interior of the casing 12. The 105 passage 30 may communicate with any con-
venient portion of the main 5, and the pres-
sure in the chamber will vary, in response to variations of pressure within the main. If the pressure within the main is reduced 110 by any cause other than a flow through the main, the diaphragm 27 will permit the frame 26, and, consequently, the clock mech-
anism, to lower with the float 8, and, conse-
quently, the clock mechanism will not be re-
leased and will not transmit an alarm signal. During period of flow, the chamber 29, and, 115 consequently, the diaphragm 27, are sub-
jected to the reduction of pressure oc-
casioned by the flow through the main, but the mercury in the tubing 7 is subjected to the additional reduction, caused by the re-
stricted passage for the water, around the edge of the diffuser 6, and by the ejector 120 action of the water passing the diffuser, and, consequently, the float 8 will continue to move downwardly, after the frame 26 has come to a position of rest.

The frame is shown in the drawings pro-
vided with an adjustable weight 32, and it 130

will be understood that the position of the arm 28, relative to the pivotal point of the frame 26, is such, that the frame and the float will move in exact synchronism, in response to variations of pressure, caused by conditions other than flows through the main 5. With this arrangement, the lower device will transmit an alarm signal, when a flow takes place through the main, and will remain inoperative during periods of no flow. When the flow through the main has ceased, the float 8 and the frame 26 will attain their normal relative positions, irrespective of the existing pressures within the main, and will transmit the "all right" signal, as has been described.

In the drawings, I have shown the portion of the main 5, in which the diffuser is located, extending vertically, so that the diffuser moves to the normal or inoperative position by its own weight, after the flow through the main has ceased and the water pressure on both sides of the diffuser are equalized. It will be apparent that any suitable means, such, for example, as a spring may be employed for moving the diffuser to the normal position, after the flow, and that various changes may be made in the apparatus, without departing from the spirit and scope of my invention.

What I claim is:—

1. In combination with a distribution system, an alarm device, a flow responsive means comprising a diffuser located in said system and subjected to variations of pressure, and means responsive to variations of pressure to which said diffuser is subjected for controlling the operation of said alarm device.

2. In combination with a distribution system, an alarm device, flow responsive means, comprising a diffuser, subjected to the flow through said main, and pressure responsive means communicating with said diffuser for controlling said alarm device, and pressure responsive means, responsive to variations of pressure within said system for rendering said flow responsive means inoperative, except in response to variations caused by flows through said system.

3. In combination with a distribution system, an alarm device, flow responsive means comprising a diffuser mounted in said system, a mercury column communicating with said diffuser and float actuated means for controlling the operation of said alarm device, and a pressure responsive means for moving said alarm device to render said float actuated means inoperative, except in response to variations caused by flows through said system.

4. In combination with a distribution system, a device for transmitting an alarm and an all right signal, pressure responsive means communicating with a restricted por-

tion of said distribution system for actuating said device, and pressure actuated means communicating with an unrestricted portion of said system for rendering said first mentioned means inactive, except in response to variations caused by flows through said system.

5. The combination in a distribution system of an alarm device, a diffuser for restricting the flow through the system, means communicating with the restricted portion of the system for actuating said device, and pressure actuated means communicating with an unrestricted portion of the system for rendering the first mentioned means inactive, except in response to variations caused by the flows through the system.

6. In combination in a distribution system, an alarm device, means actuated by variations in pressure at a restricted portion of the system for actuating the alarm device, and pressure actuated means communicating with an unrestricted portion of the system for rendering the first mentioned means inactive in actuating the alarm device, except in response to variations in pressure caused by flows through the system.

7. In combination in a distribution system, an alarm device, means, subjected to a reduction of pressure occasioned by an ejector action of the water flowing through the system, for actuating the alarm device, and means subjected to the static or head pressure within the system for rendering the first mentioned means inactive, except in response to variations caused by flows through the system.

8. In combination with a distribution system, an alarm device, means responsive to variations in pressure, occasioned by variations in flow through the system, for actuating said device, and means, responsive to static or head pressure, for rendering said first-mentioned means inactive, except in response to variations in pressure occasioned by flows through the system.

9. In combination with a distribution system, an alarm device comprising a clock mechanism, a signal wheel actuated by the mechanism, and an alarm device controlled by the signal wheel, means for engaging stops provided in the clock mechanism and for thereby controlling the operation of the signal wheel, pressure responsive means for controlling the operation of said first-mentioned means and means responsive to variations in static or head pressure within the system, for shifting the position of the clock mechanism in conjunction with variations in the position of said first-mentioned means, and for thereby rendering said first-mentioned means inactive, except in response to variations in pressure occasioned by flows through the system.

10. In combination with a distribution

system, an alarm device, controlling means for controlling the operation of the alarm device, a diffuser for occasioning variations in response to flows through the system, 5 means subjected to the variations of pressure occasioned by the diffuser, for controlling the operation of said controlling means, and pressure responsive means responsive to variations in pressure within the system,

for shifting the position of the alarm device ¹⁰ and for thereby rendering the controlling means inactive, except in response to flows through the system.

JAMES D. NELSON.
